UNITED STATES PATENT OFFICE.

RAYMOND W. DULL, OF LA GRANGE, ILLINOIS, ASSIGNOR TO THE RAYMOND W. DULL COMPANY, OF CHICAGO, ILLINOIS, A CORPORATION OF ILLINOIS.

MACHINE FOR WASHING GRAVEL OR OTHER MATERIALS.

1,280,688.

Specification of Letters Patent.

Patented Oct. 8, 1918.

Application filed September 18, 1914. Serial No. 862,401.

To all whom it may concern:

Be it known that I, RAYMOND W. DULL, a citizen of the United States of America, and resident of La Grange, Cook county, 5 Illinois, have invented a certain new and useful Improvement in Machines for Washing Gravel or other Materials, of which the following is a specification.

My invention relates to machines for 10 washing gravel or other similar materials; it relates more particularly to machines for this purpose in which a rotary receptacle containing water is arranged to receive the gravel or other materials at one end, and 15 provided with means for causing the said materials to rise and fall and gradually travel to the other end of the said receptacle. By thus agitating the gravel or other materials in a rotary receptacle containing wa- 20 ter the said materials are washed clean and smooth. My invention relates more especially to means for causing gravel or other materials to progress from the receiving end of the rotary receptacle to the discharge end 25 thereof. In addition, my invention contemplates a gravel washing machine of this kind having a tapered screen secured at its smaller end to the discharge end of said receptacle.

30 Generally stated, the object of my invention is to provide a novel and highly efficient washing machine of the foregoing general character.

Special objects are to provide novel and 35 effective means for insuring the steady and desired progress of the materials from the receiving end of the rotary receptacle to the discharge end thereof, during the operation of the machine, and for pre- 40 venting gravel or other materials from cutting away or wearing out certain portions of the machine; to provide an im- 45 proved construction and arrangement whereby the speed or progress of the gravel or other materials through the rotary receptacle may be changed or varied at will; to pro- 50 vide an improved construction and arrangement whereby a tapered screen is secured to and supported by the discharge end of the 55 rotary washing receptacle, thereby screening the relatively fine materials from the relatively coarse portions thereof as they are discharged from the rotary washing receptacle; to provide a novel construction and arrangement whereby the washing fluid,

such as water, flows from the discharge end of the receptacle toward the receiving end thereof, so that the water and materials practically travel in opposite directions while the machine is in operation; and to provide 60 certain details and novel features of construction and combinations tending to increase the general efficiency and serviceability of a gravel washing machine of this particu- 65 lar character.

To these and other useful ends, my invention consists in matters hereinafter set forth and claimed.

In the accompanying drawings—

Figure 1 is a longitudinal vertical section 70 of a gravel washing machine embodying the principles of my invention.

Fig. 2 is a front end elevation of the said machine.

Fig. 3 is a vertical cross section on line 75 3—3 in Fig. 1.

As thus illustrated, my invention comprises a body frame A adapted to rest upon the ground or on a floor. Said frame is pro- 80 vided with flanged wheels *a* for engaging the annular tracks *a*¹ on the horizontally dis- posed and rotary cylinder B, which latter is arranged longitudinally of the said frame or body. The said cylinder is provided at one 85 end with a receiving opening *b* and at the other end with a discharge opening *b*¹, the said receiving opening being preferably somewhat larger than the other opening, whereby the water C in the receptacle will 90 flow to the left and be discharged through 95 the opening *b* and into the spout *b*² arranged adjacent said opening. The water can be fed into the rotating receptacle in any suitable manner. The said receptacle is pro- 100 vided interiorly with longitudinally dis- posed ribs *b*³ disposed at such an angle that when the receptacle is rotated in the direc- tion indicated by the arrow in Fig. 3 the gravel or other materials will be carried up- ward upon the flat surfaces of these ribs to a point near the top of the receptacle.

A hopper D is arranged for introducing the gravel or other materials through the opening *b*, and a tapered screen E receives the said materials from the other end of said receptacle. Said screen is tapered and se- 105 cured at the smaller end to the discharge end of the receptacle. This can be done in any suitable manner, as by providing the said screen with an angle iron collar *e* which is 110

bolted or otherwise fastened to a similar collar on the said receptacle. Thus the materials are screened after being washed. The means for causing the materials to progress slowly through the receptacle B are as follows:—A pair of channel irons F are arranged to extend parallel and longitudinally through the receptacle B and into the screen E, being disposed a suitable distance apart and supported at their ends by bars f and f¹ mounted in any suitable manner upon the body frame, and the extension F¹ of these beams being inclosed by the screen. These channel irons F are provided within the receptacle B with a series of cross pieces f², each cross piece being in the form of a piece of angle iron, and each said angle iron forming a shelf for catching the gravel or other materials. In other words, when the receptacle B is rotated, the shelves f receive the gravel or other materials from the elevating ribs b³, and inasmuch as the vertical flanges of these shelves are all disposed toward the receiving end of the receptacle, it follows that each shelf becomes filled with gravel and then overflows at the edge thereof toward the discharge end of the receptacle. The angle irons G are arranged parallel and longitudinally of the receptacle and screen, and within the same, and are provided with similar shelves g, said angle irons being movably supported by hangers g¹ secured to the channel irons F, whereby said angle irons G may be moved endwise. For this purpose an adjusting screw g² is screw connected with the outer ends of the angle irons G, at a point immediately below the hopper D, and by rotation of this screw the said angle irons can be adjusted endwise in either direction. The overflow from the shelves f² is received by the shelves g, and the overflow from these lower shelves is then received by the body of water C at the bottom of the receptacle. It will be seen that the gravel or other materials dropping from the upper shelves to the lower shelves move forward as well as downward, so that the gravel which falls from one upper shelf will, when returned to the point above by the rotation of the receptacle, then fall upon the next upper shelf. In this way the materials are alternately raised and allowed to fall, and are in this way caused to follow an up and down or zig-zag path through the rotary receptacle, resulting in a slow traveling movement from one end of the receptacle to the other. Each time the materials are dropped from a point above they are finally received by the water and washed, and in addition a certain amount of the water is carried upward with the gravel or other materials, thus insuring a thorough washing action and also a smoothing of the gravel or other materials before the same reaches the discharge end of the rotary receptacle. If the screw g² is rotated

in a direction to cause the channel irons G to move to the left, then the progress of the materials through the receptacle will be reduced somewhat and will be slower than before; and, on the other hand, if said screw be rotated in the opposite direction, then the angle irons G will be moved endwise to the right as shown in Fig. 1, and the result will be that the materials will travel somewhat faster than before. Thus the speed or progress of the materials through the rotary washing receptacle can be changed or varied at will, depending upon the character of the materials and the purpose for which they are to be used.

Any suitable means can be employed for rotating the receptacle B, also the screen E, and for thereby causing the materials to be washed and screened. As shown, the body frame of the machine is provided with a longitudinally disposed shaft H having a pinion h which engages the toothed ring h¹ that encircles the rotary receptacle, this ring being preferably disposed between the tracks a¹ which travel on the supporting wheels or rolls a previously described. The other end of the shaft H is provided with a belt pulley h² by which the shaft is driven. Thus the driving power is communicated directly to the receptacle B, and it follows, therefore, that the rotation of this receptacle serves to rotate the screen.

In operation, the materials are deposited in the hopper D, and are then discharged by the spout d into the bottom of the rotary receptacle B, which latter contains the water or other washing fluid. The rotation of the receptacle causes the materials to advance from one end thereof to the other, in the manner described, until the smooth and thoroughly washed materials are discharged into the screen E at the end of the receptacle. This screen may be of any suitable character, the said walls thereof being perforated or apertured for the purpose of allowing the relatively fine materials to pass through; but the relatively coarse materials will roll or travel forward and downward on the sloping surface of the screen until they are discharged from the outer end of the latter. If desired, the bolts or fastening devices by which the screen is secured to the receptacle can be removed, any suitable provision being made for this purpose, and in this way the materials can be discharged without any screening thereof.

What I claim as my invention is:—

1. A machine for washing gravel or other materials, comprising a receptacle arranged to rotate about a horizontally disposed axis, for containing the washing fluid, means for introducing the gravel or other materials at one end of said rotary receptacle, instrumentalities including stationary means for advancing the gravel or other materials

through the receptacle to the other end thereof, and adjustable means coöperating with said stationary means to vary the speed of progress of the materials through the machine, said instrumentalities including an upper series of shelves for catching the falling gravel or other materials during the rotation of said receptacle, and a lower series of shelves for intercepting the overflow from 5 said upper shelves, said receptacle having means to carry the materials upward to the said upper shelves.

2. A machine for washing gravel or other materials, comprising a receptacle arranged 10 to rotate about a horizontally disposed axis, for containing the washing fluid, means for introducing the gravel or other materials at one end of said receptacle, instrumentalities for advancing the gravel or other materials 15 through the receptacle to the other end thereof, said instrumentalities including an upper series of shelves for catching the falling gravel or other materials during the rotation of said receptacle, a lower series of shelves 20 for intercepting the overflow from said 25

upper shelves, and means for adjusting said lower shelves to change the speed of progress of the gravel or other materials through the receptacle.

3. A machine for washing gravel or other materials, comprising a receptacle arranged 30 to rotate about a horizontally disposed axis, for containing the washing fluid, means for introducing the gravel or other materials at one end of said receptacle, instrumentalities 35 for advancing the gravel or other materials through the receptacle to the other end thereof, said instrumentalities including an upper series of shelves, an upper member for supporting said upper shelves, a lower 40 series of shelves, a lower member for supporting said lower shelves, movably supported on said upper member, and means for adjusting said lower member endwise.

Signed by me at Chicago, Illinois, this 45 third day of September, 1914.

RAYMOND W. DULL.
